UNITED STATES PATENT OFFICE

CLIFFORD L. CLARK, OF FAIRFIELD, MAINE

RULING AND PLOTTING DEVICE

Application filed June 18, 1930. Serial No. 461,873.

This invention relates to a ruling device preferably of transparent character which is adaptable for the use of navigators, surveyors and others in plotting points, laying down bearings or courses, drawing lines of position and for obtaining the geographical position, i. e. the latitude and longitude of the observer without the necessity of using supplemental devices such as parallel rulers and dividers or charts of any description.

One of the objects of the present invention resides in the provision of a rule device of the above character which will permit a desired bearing, course, etc. to be directly transposed to a simple blank sheet of paper with the aid of a pencil only. The particular problem which is to be handled can be computed by any of the well known methods using the ruling device as an adjunct thereto for plotting the points, drawing the lines, etc.

A further object of the present invention resides in the provision of a device which is adaptable for the obtaining of various kinds of navigational data involving latitude, longitude and direction and in which all of the pertinent data is available on the device itself and also in which rule guiding and plotting means is also provided on the device itself so that with the use of the device, in connection with a pencil and a sheet of paper only, the desired navigational data can be secured.

It is accordingly a further object of the present invention to provide a device of this character which will permit the use of charts, parallel rulers and dividers to be dispensed with and in which the desired data can be obtained more expeditiously than heretofore.

Further and other objects of the present invention will be hereinafter pointed out in the accompanying specifications and claims and shown in the drawings which by way of illustration show what I now consider to be a preferred embodiment of the invention.

In the drawings:

Figure 1 shows my improved rule somewhat enlarged; and

Fig. 2 shows a diagram illustrating one manner of use of the rule for securing certain navigational data.

In more detail the rule comprises a sheet 10 of transparent material such as celluloid or the like. The size may be varied in accordance with the degree of accuracy desired. In practice, however, a convenient size is about 4" by 7". Preferably the marginal edges of the rule are bevelled so that these edges may be more conveniently used for ruling lines. There is also provided rule guiding and plotting means preferably comprising a centrally disposed ruling slot designated 11. This slot should be comparatively narrow to permit the insertion of a fine pencil point and also it is desirable that the edges be somewhat bevelled. This slot 50 at the top and bottom terminates at the ends 55 of the 30° scale.

The ruling device is suitably engraved, cut or printed upon one face or upon both faces with certain graduations and scales which will be hereafter more fully described. If desired, certain scales or graduations can be placed on one face and others upon the other or all of the graduations and markings can be placed on one face.

Protractor graduations

Around the outside marginal edges of the rule there are provided protractor graduations 12. Preferably these are graduated to 80 single degrees, but other scales might be employed if desired. These protractor markings correspond to the various degree point markings of a compass and are used in calculations involving compass bearings. Preferably every tenth graduation is numbered as shown with the proper degree number. Preferably the numbering of the protractor graduations is such that two sets of numbers are included, one set running from 0 to 90° 85 90

being provided for each quadrant and a second set running from 0 to 360° being provided for the complete set of protractor graduations. Thus it will be noted that the two extremities of the line of the slot 11 will be 0° – 360° and 0° – 180° and a line at right angles to this groove and bisecting it will align with 90° – 90° and 90° – 270° .

10   *Longitude scale*

The longitude scale is comprise of a series of equidistant parallel straight lines 13 which run both lengthwise and crosswise on the transparent member, and which divide the entire face of the rule into equal squares which may be proportioned to a dimension of for example one-tenth of an inch to a side. This arrangement of graduations represents the scale of a Mercator projection or chart, one-tenth of an inch being equivalent to $(1')$ one minute of longitude on the equator. Since on a Mercator projection the units of longitude are made to appear everywhere equal, it will be apparent that the longitude scales will remain constant for use in any latitude. Preferably for facility in reading, every fifth line 13 is displayed relatively more boldly or by a heavier line.

30   *Latitude scales*

There are also a series of straight latitude scales 14 provided on the transparent member which run lengthwise of the rule as shown and which are parallel with each other. These scales cover the entire face of the rule except at the border portions where the protractor and longitude scales are shown. These scales 14 are provided one for each degree of latitude from 0° , the equator, to 60° north or south or further if desired. Each of the latitude scales is graduated proportionately to the previously mentioned longitude scales on the Mercator principle.

45   For a further explanation reference may be had to the American Practical Navigator by Bowditch, Chapter II, article 43. Hereafter for convenience in expression, the portion of the rule covered by the latitude scales will be termed the "graph". The parallels of this graph are so spaced that the distance between any adjacent two of them is preferably .05 of an inch or $30''$ (30 seconds) i. e. one-half minute of longitude. Accordingly, it will be appreciated that longitude can be measured lengthwise or across and between any two points on the rule.

55   The scales 14 are individually graduated with a series of small dots or dashes 15 and the space between any adjacent two of these dot or dash graduations upon any individual scale 14 is equivalent to one minute of latitude $(1')$ or one nautical mile. Every fifth latitude parallel on the graph is graduated by dashes

to facilitate reading and these particular scales are numbered at their extremities with the proper latitude degree number. For example 0° – 5° – 10° – 15° , etc. Each set of the dot graduations on $(5')$ five minute intervals are shown by heavy curved lines 16. These lines 16 beginning with the central transverse line of graph which is a straight line and designated at $0'$ are numbered at both extremities as $5'$ – $10'$ – $15'$, etc. Every fifth dot graduation curved line is shown boldly by a heavy continuous line to facilitate reading.

70   Referring again to the longitude scales 13, it will be noted that upon the graph portion of the rule that the $1'$ graduations of longitude are further sub-divided by intermediate parallel transverse lines 17. These lines 17 in conjunction with the parallels of the latitude scales divide the face of the graph into equal squares of $\frac{1}{20}$ of an inch or $\frac{1}{2}$ minute of longitude. All of these parallel lines across the graph are thus closely spaced in order that any point on any of the latitude scales may be more accurately transferred perpendicularly over to the pencil slot so that a point can be plotted therein in an accurate manner.

75   In the use of the rule it is intended that the use of charts be wholly dispensed with. Furthermore no parallel rulers, dividers or like devices need be used. All that is needed is the rule, a sheet of blank paper which is placed under the rule and a sharp pencil together with a knowledge of the manner of use of the rule. The rule itself contains on its face all of the requisite longitude data, all of the requisite latitude data and all of the protractor data which is required for working out various navigational and like problems involving latitude, longitude and direction.

90   *Method of using rule*

100   Various of the sundry plottings, laying down of bearings and courses and drawing of lines of position can be obtained by the use of the rule and the rule is also adaptable for use to obtain the same results in a variety of ways. For the purpose of explaining what is considered to be the most convenient method of using the rule there has been selected the example given in Chapter XV, Article 380, H. O. #9 (Bowditch) wherein the intersection of two Sumner lines, i. e. the ship's position, is found by computation, the ship's run between observations being involved and the foregoing illustrative example will show the same results obtained graphically by the use of this rule with accompanying pencil and paper. The example reads as follows:

105   "Taking two Sumner lines — defined by the latitude and longitude of a point of each and the respective azimuths of the celestial

bodies upon which the lines depend, as follows:

- 5 A. $\{ 25^{\circ} 40' S. \}$ Azimuth at right angles
 $\{ 115^{\circ} 31' W. \}$ to line, N. $51^{\circ} E.$
- B. $\{ 25^{\circ} 25' S. \}$ Azimuth at right angles
 $\{ 115^{\circ} 33.5' W. \}$ to line, N. $72^{\circ} W.$

and supposing the vessel from which the observations were taken that gave these lines to have run N. $54^{\circ} E.$ (true) 35 miles in the interval between the sights, find the position of the vessel at the time of the second sight."

For the purpose of explanation, let the extremity of the line containing the pencil slot 11 marked 0° – 360° be called North, the opposite extremity marked 0° – 180° South, the extremity of the central or $0'$ line of the graph marked 90° East and its opposite marked 90° – 270° West.

With the rule, first draw on a blank sheet of paper two lines 1 and 2 (see Fig. 2) which intersect each other at right angles. Either the slot 11 or the sides of the rule can be used to obtain the 90° relation of the lines. Let line 1 represent parallel of latitude $25^{\circ} 40' S.$ and line 2 meridian of longitude $115^{\circ} 31' W.$ The intersection of these lines is the point A through which the first Sumner line or line of position is to be drawn, but since this line must be advanced in a direction N. $54^{\circ} E.$ (true) 35 miles, i. e. the ship's run between sights, it is unnecessary to draw the line through point A here.

Now place the center of the protractor, North end toward top of diagram over the point A in such manner that the pencil slot 11 coincides with the meridian line 2. Plot a point where the 54th graduation of the protractor, east of North, cuts the paper. Call this point a . Slide the rule around to such a position on the paper that both points A and a are centered in the pencil slot, point A being in a position perpendicular to the intersection of the $25'$ curve with the 25° latitude scale at the South end of the rule. This is done with sufficient accuracy by the guidance of the closely spaced parallel lines cutting all latitude scales perpendicularly. From this intersection, measure off on the 25° latitude scale $35'$ or miles. This brings us to a point on the North end of the rule where the $10'$ curve intersects the scale. Transfer this point perpendicularly to the pencil slot and call it A'. A' then is the point 35 miles N. $54^{\circ} E.$ from the point A through which the first Sumner line N. $39^{\circ} W.$, at right angles to the azimuth A is to be drawn.

Place center of the rule and the protractor over point A' so that the parallel of latitude $25^{\circ} 40' S.$ coincides with or is parallel to any of the East and West lines on the rule. Plot a point where the 39th graduation of the protractor, West of North, cuts the paper. Call this point a' . Draw straight line through

points A' and a' . A' a' is the first Sumner line.

Next, to draw second Sumner line, place rule with North end toward top of diagram, in such manner that meridian $115^{\circ} 31' W.$ coincides with 35° latitude scale and parallel of latitude $25^{\circ} 40' S.$ cuts the 25° latitude scale at its intersection with the $15'$ curve on South end of rule. Plot point at center of rule, this is point B in latitude $25^{\circ} 25' S.$ longitude $115^{\circ} 33.5' W.$ through which the second position line is to be drawn running N. $18^{\circ} E.$ at right angles to azimuth B.

Without moving rule from its former position, plot point b where the 18th graduation of the protractor, east of North, cuts the paper. Draw straight line through points B and b intersecting line A' a' at C. Bb then is the second Sumner line and C is the ship's position at the time of the second observa-
 80
 85

tion.
 90
 95
 100

Now move the rule with North end toward top of diagram to such position that point C falls in the 25° latitude scale, parallel $25^{\circ} 40' S.$ cuts same scale at its intersection with the South $25'$ curve and is parallel to the East and West lines of the rule. The latitude and longitude of the point C can now be read off the face of the rule as heretofore explained. This is found to be latitude $24^{\circ} 54' S.$ longitude $115^{\circ} 22.5' W.$, the ship's position at the time of the second sight.

The foregoing example has shown how the rule can be utilized for plotting points, laying down courses and bearings and obtaining the ship's position. Other uses will be apparent to those familiar with problems of this character and the particular manner of computing the data necessary in the solution of such problems may be varied as desired.
 100
 105

The data to be employed in using the rule can be obtained in connection with the solution of any problem of the position line whether Sumner's, Marc St. Hilaire's, Weems' or any of the methods explained by the Hydrographic Office publications be used.

What I claim is:

1. A rule device for plotting points and ruling lines upon sheets of paper, said rule comprising a transparent member provided with a pencil receiving ruling and plotting slot therein, said transparent member having thereon two sets of longitude scales, each set extending substantially completely across the transparent member and the respective sets being at right angles to each other to form a series of square rulings over substantially the entire face of the transparent member, latitude scales and protractor graduations for the purpose described.
 115
 120
 125

2. A rule device for plotting points and ruling lines upon sheets of paper, said rule comprising a transparent member with a pencil receiving ruling and plotting slot
 130

therein, said transparent member having graduated over substantially its entire surface parallel lines representative of longitude scales, and also having graduated thereon superimposed parallel latitude scales, said member also having graduated thereon protractor graduations, said transparent member also having in addition curved lines to aid in reading the graduations of the latitude scales, said curved lines diverging from the adjacent curved lines as they progress from the zero latitude scale to higher latitude scales.

3. A ruling device for plotting points and 15 ruling lines upon sheets of paper, said ruling device comprising a transparent member provided with a pencil receiving ruling and plotting slot therein, said transparent member having longitude scales disposed lengthwise and transverse thereof with the pencil slot parallel to the scales which extend in one direction, said member also having latitude scales disposed to intersect and extend above and below a transverse median line 20 which intersects the pencil slot at right angles and which is representative of 0 minutes of latitude on any of the latitude scales.

In testimony whereof I hereto affix my signature.

39 CLIFFORD L. CLARK.
